UNITED STATES PATENT OFFICE.

HENRY P. CLAUSEN, OF MOUNT VERNON, NEW YORK, ASSIGNOR TO WESTERN ELECTRIC COMPANY, INCORPORATED, OF NEW YORK, N. Y., A CORPORATION OF NEW YORK.

AUTOMATIC TELEPHONE SYSTEM.

1,308,841.

Specification of Letters Patent.

Patented July 8, 1919.

Application filed May 24, 1918. Serial No. 236,373.

To all whom it may concern:

Be it known that I, HENRY P. CLAUSEN, a citizen of the United States, residing at Mount Vernon, in the county of Westchester, 5 State of New York, have invented certain new and useful Improvements in Automatic Telephone Systems, of which the following is a full, clear, concise, and exact description.

This invention relates to telephone systems 10 employing automatic switching apparatus for the purpose of establishing conversational connections and particularly to systems of this character having a capacity for a large number of subscribers' lines.

15 In telephone systems comprising a plurality of central offices and a comparatively large number of subscribers' lines, in which switching facilities are provided such that a subscriber may extend a connection from 20 his own office into any of the other offices, and finally complete the connection to a desired line therein, it often becomes necessary for the subscriber in so extending his line to set up a long train of switching mechanisms consisting of several selective switches. 25 It may frequently happen that the calling party, in building up a connection of this character where a large number of digits is concerned, inadvertently manipulates his

30 sender to transmit an improper digit after having partly completed a connection over a number of the switches in the train. The result is that the particular switch which is being operated at the time the improper digit is sent is not set in operative relation 35 to the desired group of trunks. It is, therefore, necessary that the falsely set switch be restored to its normal position before the call may be proceeded with, and it is more- 40 over desirable that such switch be restored to the exclusion of, and without affecting the preceding switches in the connection. This feature is of special advantage in large

45 systems since it enables the calling party to retain, to the exclusion of other subscribers, the use of that portion of the train of switches successfully operated up to the point where the wrong digit is sent.

Considering again telephone systems of 50 the above mentioned character wherein a plurality of central offices are concerned, and wherein private branch exchanges are associated with the central offices, with switching facilities whereby any subscriber

in the system may obtain connection with 55 any other subscriber, it frequently occurs that a long train of switches must be employed in extending a connection to a subscriber's line belonging to one of the private branch exchanges. This will neces- 60 sarily be true where the calling line is individual to some office other than that with which the private branch exchange containing the called line is associated. In view of this necessity of setting up long trains 65 of switches, and further in view of the fact that a calling subscriber, regardless of the office to which his line belongs, after having completed a conversation with one subscriber to a private branch exchange very 70 often wishes to get in touch with another subscriber to the same exchange, it becomes desirable that he be able to release only that portion of the train of switches which is located in the private branch exchange, 75 without disturbing the remaining switches. The set switches in his own and in all other central offices preceding the called private branch exchange may therefore be retained to his exclusive use while he proceeds in the 80 usual manner to set other switches in the called exchange to obtain connection to other subscribers' lines.

In view of the foregoing, the present invention has as its general object the provision 85 of a telephone exchange system equipped with means whereby a calling subscriber may, either during the process of extending a connection over a train of switches, or after having completed the connection to a called line, release a portion 90 only of such train of switches, leaving undisturbed the preceding switches employed in the extension of the connection.

A feature consists in the provision of 95 means associated with one of the switches of a train of operated switches which is responsive only to a characteristic series of impulses sent from the calling substation to affect the electrical condition of the release 100 trunk leading back to the next preceding switch in the train. This condition serves to bring about the restoration of such switch, which, however, in releasing does not cause the release of the remaining 105 switches, but is adapted to guard against the application of the releasing condition to the release trunk leading back therefrom.

Another feature consists in the arrangement whereby any one of a series of selective switches may be operated by impulses sent out by the calling subscriber to advance 5 in its primary movement through a distance sufficient to bring about a change in the electrical condition on the release trunk extending to the preceding set switch, thereby resulting in the restoration of both of said 10 switches.

Other features of the invention will be made apparent in the progress of the following description.

In the drawings accompanying this specification, Figure 1 shows a portion of a telephone system arranged in accordance with one embodiment of the invention. This figure illustrates subscribers' lines and substations and selective switches for interconnecting the same, together with means whereby any one of a train of selective switches may be operated in its primary movement by the calling subscriber at any point in the process of extending a connection 20 to cause the release only of the next preceding set switch, while all other switches between the one released and the calling line remain intact in their operated positions. Fig. 2 is a showing in part of a telephone system involving another embodiment of this invention. This figure depicts a system having subscribers' lines with automatic switches for interconnecting the same, and also means associated with the final or connector switch employed in a completed connection which is responsive only to a characteristic series of impulses transmitted from the calling substation to effect the release of the switch immediately preceding, to the 25 exclusion of all other switches in the train.

Referring particularly to the embodiment shown in Fig. 1, wherein there is provided means for permitting the calling subscriber, in extending his line over a long train of 30 switches, to release the switch last operated upon discovering that he has sent an improper series of impulses to set such switch, a description will first be given of the operation of extending a call through from the calling substation A to the called substation B. Before proceeding it is to be observed that while the drawing discloses a train of switches comprising a line finder indicated by its brushes 100, 101, 102; a connector indicated by its brushes 103, 104, 105 and two intermediate selectors S and S', there may be inserted any number of selector switches in accordance with the size of the system.

When the subscriber at station A removes 35 his receiver from its hook, the resulting closure of the line 106, 107, causes the finder switch to operate in the well-known manner to search out and connect with the calling line. This extends the calling line to a first 40 selector, which for the purpose of the present

description is assumed to be inserted in the series between the finder and the selector S shown in detail. The calling subscriber operates his dial 160 to set the first selector on the desired group, and the automatic hunting movement thereupon ensuing extends the line over trunk 108, 109, 110 to an idle second selector, as the switch S. Upon the extension of the connection to switch S, a circuit for the line relay 111 is closed from 45 free pole of battery, through the upper winding of relay 111, back contact and upper armature of relay 112, conductor 109, through the first selector (not shown), finder brush 101, conductor 107, over the loop of 50 substation A, conductor 106, brush 102, through the first selector (not shown), conductor 110, inner lower armature and back contact of relay 112, lower winding of relay 111 to ground. Relay 111 energizes and 55 closes a circuit from battery, through the winding of slow relay 113, front contact and armature of relay 111, contact 114 to ground. Relay 113 by attracting its upper armature places a ground on release trunk 108 which 60 serves to prevent the release of the preceding switch as will clearly be shown hereinafter in connection with the present description of selector S. Relay 113 at its lower armature inserts a break in the circuit of release 65 magnet 115, and also prepares a circuit for the primary stepping magnet 116.

The calling subscriber now manipulates his dial 160 to transmit a group selecting series of impulses to switch S. At each interruption of the line circuit, relay 111 vibrates its armature and closes the following operating circuit for the magnet 116; grounded contact 114, armature and back contact of relay 111, contact and middle 70 lower armature of relay 112, lower armature and front contact of relay 113, winding of slow relay 117, through the winding of magnet 116 to battery and ground. Relays 113 and 117 being constructed to release 75 their armatures slowly remain operated during the sending of impulses. The magnet 116 responds to the closure of its circuit and operates to advance brush shaft 118 step by step in the primary direction, and finally 80 brings the brushes 119, 120, 121 to rest in operative relation to the group of terminals of trunks leading in the proper direction. The energization of relay 117 closed a circuit from battery, through the winding of 85 relay 122, armature and front contact of relays 117 to ground. Relay 122 attracts its armatures and as soon as the shaft 118 takes its first primary step, a holding circuit is completed as follows for said relay 122: battery, through winding of test relay 122, front contact and inner armature thereof, primary off-normal contact 123, right-hand armature and contact of magnet 124, conductor 125, to ground at the upper armature 90

of relay 113. On the cessation of the line interruptions relay 111 remains energized and after a short period slow relay 117 retracts its armature. A circuit is thereupon closed for the secondary stepping magnet 124 from battery, through the winding of magnet 124, left-hand armature and contact of said magnet, back contact and armature of relay 117, front contact and inner armature of relay 122, contact 123, right-hand armature and contact of magnet 124, conductor 125, to ground at the upper armature and contact of relay 113. Magnet 124 energizes to advance brushes 119, 120, 121 onto the first set of terminals in the chosen group, and by attracting its left-hand armature opens its own circuit. The attraction of the right-hand armature of magnet 124 also severs the above traced holding circuit of relay 122. The test brush 119, however, reaches the test terminal of the first set slightly before the armatures of magnet 124 are completely attracted. If then it be assumed that the first trunk is busy a ground potential will be found by test brush 119 on the test terminal 126, and the following circuit is closed for relay 122 prior to the interruption of its original holding circuit: battery, through the winding of relay 122, front contact and inner armature thereof, test brush 119, to the busy grounded terminal 126. Relay 122 therefore remains energized and magnet 124 on retracting its armatures again closes its energizing circuit to advance brushes 119, 120, 121 step by step over all busy terminals. This operation continues until an ungrounded test terminal 126 is found, at which time relay 122 deenergizes, opening the circuit of magnet 124 to thereby arrest brushes 119, 120, 121 on terminals 126, 127, 128 of a trunk leading to the switch S'.

On the retraction of the armatures of relay 122, the following preliminary circuit is completed for relay 112: battery, through the winding of such relay, right-hand armature and contact of magnet 115, back contact and inner armature of relay 122, contact 123, right-hand armature and contact of magnet 124, to ground at the upper armature and contact of relay 113. Relay 112 on energizing extends trunk conductors 109 and 110 through to switch S', and thereby completes as follows, a circuit for line relay 129: battery, through the upper winding of relay 129, back contact and uppermost armature of relay 130, terminal 127, brush 120, front contact and uppermost armature of relay 112, conductor 109, thence over the loop of substation A as described, returning by way of conductor 110, inner lower armature and front contact of relay 112, brush 121, terminal 128, inner lower armature and back contact of relay 130, lower winding of relay 129, to ground. Relay 129 closes a

circuit from battery through the winding of slow relay 131, front contact and armature of relay 129, to ground at the closed contact 132.

At the time relay 112 was energized, it 70 opened the circuit of line relay 111, which interrupted the circuit of relay 113. After a sufficient interval has elapsed, relay 113 retracts its armatures and opens the above traced preliminary energizing circuit of relay 112. In the meantime, however, and before this occurs, the relay 131 at switch S' has been energized as explained, and establishes the following substitute circuit for relay 112: battery, through the winding of relay 112, right-hand armature and contact of magnet 115, back contact and inner armature of relay 122, brush 119, terminal 126, contact 133, to ground at the upper armature and contact of relay 131. The presence of ground on terminal 126 renders the switch S' busy to other switches. Relay 113 at switch S on releasing opens the ground connection to wire 125. The off-normal contact 134 having been actuated when the switch S took its first primary movement, a ground is maintained on the test wire 108 to prevent release of the preceding switch.

The mechanism is now ready to receive the next set of directive impulses, and the 95 calling party by manipulating dial 160, causes a corresponding series of interruptions in the above traced circuit of line relay 129. For each retraction of the armature of relay 129, the following circuit is closed 100 for the primary stepping magnet 135, which operates to advance brushes 136, 137, 138 step by step in the primary movement: grounded contact 132, armature and back contact of relay 129, contact and middle 105 lower armature of relay 130, lower armature and front contact of relay 131, through the windings of slow relay 139 and magnet 135 to battery. Relay 139 closes a circuit for relay 140, which in turn locks up over 110 a circuit traceable from battery, through the winding of relay 140, front contact and lower armature thereof, contact 141, closed on the first step of the shaft 149, right-hand armature and contact of secondary magnet 115 142, to ground at the armature and contact of relay 131. When the sender 160 restores, the line relay 129 remains permanently energized and after a brief interval slow relay 139 retracts its armature. Deenergization 120 of relay 139 establishes a circuit from battery, through the winding of secondary stepping magnet 142, left-hand armature and contact thereof, back contact and armature of relay 139, front contact and lower armature of relay 140, contact 141, to ground as above traced at the upper armature of relay 131. The magnet 142 operates in a manner similar to that already described in connection with the secondary movement of switch 125 130

S to advance brushes 136, 137, 138 over the selected group, and into engagement with terminals 143, 144, 145 of a trunk leading to an idle connector switch. When test brush 136 reaches the non-grounded terminal 143, the test relay 140 deenergizes as hereinbefore described and stops the hunting movement. Relay 140 by retracting its armatures closes as follows a circuit for relay 130: battery, through the winding of relay 130, right-hand armature and contact of magnet 146, back contact and lower armature of relay 140, to ground at the armature and contact of relay 131 over the path previously traced. Relay 130 on energizing extends the connection through to the connector 103, 104, 105, and completes a circuit for the line relay (not shown) at said connector. In the well-known manner the energization of the connector line relay causes the application of a ground back upon the test terminal 143 at switch S' to provide a new holding circuit for relay 130 prior to the disruption of its original circuit by the deenergization of slow relay 131. This circuit for relay 130 is traceable from battery, winding of such relay, right-hand armature and contact of magnet 146, back contact and lower armature of relay 140, brush 136, to the grounded terminal 143.

The calling subscriber now operates his sender 160 to send the last two series of impulses, which control the movement of the connector switch to finally complete the extended connection to the line of the substation B.

When conversation has been finished, either the calling subscriber by replacing his receiver, or the calling and called subscribers by both replacing their receivers, will cause in the well-known way the release of the connector; and the removal of ground from test terminal 143. The removal of ground from terminal 143 causes the deenergization of relay 130, which retracts its armatures and closes the following circuit for release magnet 146: battery, through the winding of said magnet, primary off-normal contact 147, back contact and lower armature of relay 131, middle lower armature and contact of relay 130, back contact and armature of relay 129, to grounded contact 132. Magnet 146 energizes to release switch S' to normal position. As soon as the switch is completely restored, contact 148 opens and removes ground from test terminal 126, which results in the restoration of the switch S in a manner similar to that just described for switch S'. All switches preceding selector S are likewise restored to normal.

The case will next be assumed in which the calling party at A in building up a connection to the called line inadvertently sends out a false set of impulses to set a

switch such as selector S in relation to some trunk group other than the desired group. As soon as the switch S has completed its secondary movement and has chosen an idle trunk in the false group, which for the purpose of the present discussion will be considered as a trunk leading to selector S', a circuit for the line relay 129 is closed. This circuit has already been traced and need not be again described. The calling subscriber now transmits a special series of eleven impulses, the sender 160 being constructed to accomplish this purpose, to the switch S', resulting in the brush shaft 149 being advanced eleven primary steps. On 80 the shaft 149 taking its eleventh step, a special contact 133 in the release trunk is opened. This removes both the ground at primary off-normal contact 148 and the ground at the primary off-normal contact 134 from test terminal 126. The previously traced circuit for relay 112 is therefore opened and said relay deenergizes. Upon the two inner armatures of relay 112 reaching their back contacts, relay 111 is again 90 energized since the line 106, 107 is closed at this time. Relay 111 attracts its armature to place a break point in the above described circuit of release magnet 115, and also causes the energization of relay 113. 95 However, during the retraction of the lowermost armature of relay 112, the contact 114 is so constructed as to maintain a momentary engagement therewith after having made connection with its grounded contact 150. This results in a momentary ground being placed on conductor 151, which causes the energization of magnet 115. Magnet 115 locks up over off-normal contact 152, and restores selector S to normal. 105 A form of relay contact which closes a circuit momentarily on the back stroke of its armature in the manner described in connection with the lowermost armature of relay 112 and lowermost armature of relay 110 130 is shown and described in the copending application of Clausen, Serial No. 208,844, filed December 26, 1917. On reaching its fully restored position, shaft 118 opens contact 134, but relay 113 being energized at 115 this time maintains a ground on release trunk 108, and hence the preceding switches in the train are left undisturbed. As soon as the switch S removes its brushes 120 and 121 from terminals 127 and 128, the circuit of 120 line relay 129 is opened resulting in the closure of the circuit of release magnet 146 in the manner already described. Switch S' thereupon restores to normal. The calling subscriber may proceed with the dialing operation at the point where the false digit was sent.

A description will now be given of the embodiment of the invention shown in Fig. 2. This modification of the invention is ob- 130

viously well adapted to use in private branch exchanges where it is often desirable for an outside calling subscriber to obtain several successive connections with different 5 subscribers in the same exchange. There are shown the detailed circuits of a connector C and a selector S² which may well be considered as located in a private branch exchange, and while there is indicated only a 10 finder switch by its brushes 200, 201, 202, and a selector by its brushes 203, 204, 205, such as may be situated in a central office, it is to be understood that the train of 15 switches preceding the selector S² and connector C may comprise any suitable number of switches.

Upon the removal of the receiver from its hook at the substation A', the line circuit 206, 207 is closed to initiate the operation of 20 the finder switch. The line is thereby extended to an idle selector switch having brushes 203, 204, 205, and the calling subscriber by manipulating his sender 208 sets 25 said selector on the terminals of a trunk leading to an idle selector in the desired private branch exchange, such as selector S². Upon the extension of the connection to switch S², a circuit is established for line 30 relay 209 from battery, through the upper winding of such relay, back contact and uppermost armature of relay 210, brushes 204 and 201, conductor 207, over the loop of substation A', conductor 206, brushes 202 and 205, inner lower armature and back contact 35 of relay 210, lower winding of relay 209, to ground. Relay 209 by energizing closes a circuit from battery through the winding of slow relay 211, front contact and lower armature of relay 209, to ground. 40 Relay 211 operates and at its upper armature places a ground on the test wire 212, whereby the preceding switches are prevented from releasing. This ground is applied over a circuit from the inner right-hand armature and back contact of relay 213, contact and upper armature of relay 211, closed contact 214, to test wire 212. Relay 211 at its lower armature places a 45 break in the circuit of release magnet 215, and also prepares an operating circuit for the primary stepping magnet 216.

When the calling party operates his sender 208 to produce a series of line interruptions in accordance with the second digit of the 50 called number, the line relay 209 vibrates its armatures in response to such interruptions, and for each retraction of the lower armature thereof, the following circuit is closed for the primary stepping magnet 216: 55 lower grounded armature and back contact of relay 209, contact and lowermost armature of relay 210, lower armature and front contact of relay 211, winding of relay 217, through the winding of the magnet 216 to battery and ground. Magnet 216 operates 60 to step the brushes 218, 219, 220, 221 in the primary movement into operative relation with the desired group of trunks. The slow relay 217 energizes in the circuit just traced and closes a circuit from battery, through 70 the winding of test relay 222, armature and front contact of relay 217 to ground. Test relay 222 attracts its armature and a holding circuit therefore is closed as follows: battery, through the winding of said relay 75 222, front contact and armature thereof, primary off-normal contact 223, contact and right-hand armature of the secondary stepping magnet 224, upper armature and contact of relay 211, back contact and inner 80 right-hand armature of relay 213 to ground. At the end of the primary series the line relay retains its armatures closed and after a brief interval, slow relay 217 deenergizes 85 and a circuit is thereupon established for the secondary stepping magnet 224. This circuit may be traced from battery, through the winding of said magnet, left-hand armature and contact thereof, back contact and armature of relay 217, front contact and armature 90 of relay 222, contact 223, contact and right-hand armature of magnet 224, upper armature and contact of relay 211 to ground at the back contact and inner right-hand armature of relay 213. Magnet 224 energizes to 95 advance the brushes 218, 219, 220 and 221 onto the first set of terminals of the selected group, and by attracting its left-hand armature interrupts its own circuit. Said magnet by attracting its right-hand armature also 100 opens the previously traced circuit for the test relay 222. The right-hand armature of magnet 224 is adjusted, however, so as not to break connection with its co-operating contact until slightly after the test brush 105 221 is in engagement with the test terminal 225. In the event then that the first trunk in the group is busy, a ground will be found upon the terminal 225 and the following substitute circuit is established for test relay 110 222 in the place of its original circuit, which is now open as described by the energization of the stepping magnet 224: battery, through the winding of relay 222, front contact and armature thereof, test brush 221, to the 115 grounded terminal 225. Relay 222, therefore, remains energized and magnet 224 upon retracting its armatures closes its energizing circuit again and the brushes are advanced a second step forward. This operation is 120 maintained until an idle trunk is encountered upon the test terminal 225 on which no ground is present. At this time relay 222 deenergizes, which results in bringing the switch to rest on the terminals of the idle 125 trunk.

On retracting its armature, relay 222 closes the following preliminary circuit for relay 210: free pole of battery, through the winding of relay 210, back contact and armature 130

- of relay 222, contact 223, contact and right-hand armature of magnet 224, upper armature and contact of relay 211, to ground at the back contact and inner right-hand armature of relay 213. Relay 210 by attracting its armatures extends the calling line through to the brushes 219 and 220 and thence to the connector switch C. This results in the establishment of the following
- 5 circuit for the calling line relay 226: free pole of battery, left-hand winding of said relay, contact 227, terminal 228, brush 219, front contact and uppermost armature of relay 210, brushes 204 and 201, conductor 10 207, over the loop of the calling station A', conductor 206, brushes 202 and 205, inner lower armature and front contact of relay 210, brush 220, terminal 229, contact 230, through the right-hand winding of relay 226
- 15 to ground. Relay 226 closes a circuit for the slow relay 231 from battery, through winding of said relay, front contact and left-hand armature of relay 226 to ground. Relay 231 at its left-hand armature applies a
- 20 ground potential to the test terminal 225 to render this connector busy to other selector switches. When the relay 210 energizes, it severs the hereinbefore described circuit of relay 209, which in deenergizing opens the
- 25 circuit of relay 211, which in turn by retracting its armatures opens the above traced preliminary circuit for relay 210. Relay 211, however, being slow to release, does not open the said preliminary energizing circuit
- 30 of relay 210 until after relay 231 has been energized, as described, to establish a substitute circuit for relay 210 as follows: battery, through the winding of relay 210, back contact and armature of relay 222, test brush 35 221, terminal 225 to ground at the left-hand armature and contact of relay 231. The ground on the terminal 225 is also applied back to the test wire 212 to prevent the releasing of the preceding switches after slow re-
- 40 45 50 55 60 65 70 75 80 85 90 95 100 105 110 115 120 125 130
- relay 211 deenergizes to remove therefrom the ground at the inner right-hand armature of relay 213, which has been held applied to the said test wire 212 during the operating period of the selector S². The path for the application of this new holding ground is traceable from test terminal 225, brush 221, contact 223, contact and right-hand armature of magnet 224, contact 214 to the test wire 212.
- 60 The calling subscriber again manipulates the sender 208 to transmit the tens digits and at each interruption of the line circuit, the line relay 226 retracts its armatures. At the first deenergization of relay 226, the following circuit is closed for operating the primary stepping magnet 232: left-hand armature and back contact of relay 226, right-hand armature and front contact of relay 231, winding of slow relay 233, through the winding of the magnet 232, position 1, to battery. Magnet 232 energizes and advances the brushes 235, 236 and 237 one step in the primary or group selecting direction. For each succeeding retraction of the armature of relay 226, magnet 232 operates to advance said brushes step by step into operative relation with the desired group of line terminals. During the operation of the primary stepping magnet, slow relay 233 remains energized and establishes a circuit from battery, through the winding of escape magnet 238, contact 239, armature of relay 233 to ground. At the end of the primary series of impulses, relay 233 deenergizes and opens the circuit of escape magnet 238, which in turn releases the side switch into its second position.
- Upon the transmission of the final or units series of impulses, relay 226 vibrates its armatures as before, and at each retraction thereof the following operating circuit is closed for the secondary stepping magnet 240: grounded armature and back contact of relay 226, right-hand armature and front contact of relay 231, winding of slow relay 233, outer left-hand armature and contact of relay 241, through the winding of the magnet 240, side-switch arm 234, position 2, to battery. Magnet 240 operates to advance the brushes 235, 236 and 237, step by step over the selected group of terminals in engagement with the terminals 242, 243 and 244 of the called line. Assuming the called line to be busy at this time, ground potential will be found upon the test terminal 244, having been applied thereto either from a finder or selector switch in case the line is busy as a calling line, or from a side-switch arm corresponding to arm 245 at some other connector in the event the line is busy as a called line. In either case the slow relay 233 in deenergizing at the end of the series of impulses permits the contact 239 to engage its co-operating contact before the armature of said relay breaks engagement with the said contact 239. This establishes a substitute circuit as follows for preventing the escape magnet from passing the side switch into position 3: battery, through the winding of escape magnet 238, contact 239, through the winding of relay 241, contact 246, side-switch arm 245, position 2, brush 237 to the grounded test terminal 244. Relay 241 energizes in this circuit and at its right-hand armature and make-before-break contact 246 prepares a new circuit for itself in series with the escape magnet 238 which may be traced from battery, through the winding of magnet 238, contact 239, winding of relay 241, contact 246 and right-hand armature of said relay to ground at the primary off-normal contact 247. Relay 241 also closes a circuit from the grounded secondary winding of busy tone machine 248, inner

left-hand armature and contact of relay 241 to conductor 249. Current from the busy tone machine may be transmitted in the well-known manner back to the calling substation A' to inform the subscriber thereat that the called line is engaged.

The subscriber at A' upon receiving this notification replaces his receiver on the hook, which results in the deenergization of the 10 line relay 226. After a brief interval the slow relay 231 retracts its armatures and closes the following circuit for the connector release magnet 250: from battery, through the winding of said magnet, primary off-normal contact 251, back contact and right-hand armature of relay 231, back contact and left-hand armature of relay 226 to ground. Magnet 250 operates in response to the closing of this circuit to restore the connector switch C to its normal position.

The retraction of the left-hand armature of relay 231 also removes ground from the test terminal 225 to open the above traced circuit of relay 210 which deenergizes and 25 prepares the following circuit for the release magnet 215 of the selector switch S²: battery, through the winding of magnet 215, primary off-normal contact 251, back contact and lower armature of relay 211, lower-30 most armature and contact of relay 210, back contact and lower armature of relay 209 to ground. Magnet 215 thereupon restores selector switch S² to normal. Ground is, at the same time, removed from the test conductor 212, with the result that the preceding switches in the train are restored in the well-known manner.

In case, however, the called line is idle at the time the connector C makes the test 40 thereof, no ground will be found on the terminal 244. Therefore, as the relay 233 deenergizes after the cessation of the secondary series of impulses, the circuit of the escape magnet 238 is interrupted. Escape 45 magnet 238 thereupon deenergizes and releases the side switch into its third position. In this position of the side-switch arm 245, a ground potential is placed upon the terminal 244 to render the called line busy, and 50 the following circuit is also closed for relay 253: battery, winding of said relay, contact and armature of magnet 238, side-switch arm 245 to ground. Relay 253 by attracting its armatures closes conductors 254 and 255 through to the brushes 235 and 236 respectively. Side-switch arm 234 on reaching its 55 third position closes a circuit for the ringing relay 252. This circuit may be followed from battery, side-switch arm 234, inner 60 right-hand armature and contact of ringing cutoff relay 256, through the winding of relay 252, interrupter 257 to ground. Relay 252 is intermittently actuated by the interrupter 257 to apply ringing current to the 65 called line.

The ringing circuit may be traced from the ringing source 258, front contact and lower armature of relay 252, conductor 255, lower armature and contact of relay 253, brush 236, terminal 243, over the called line 70 through the bell at substation B', returning by terminal 242, brush 235, contact and upper armature of relay 253, conductor 254, upper armature and front contact of relay 252 to ground. When the called party responds by removing his receiver from the switch hook, during the period that the ringing relay 252 is deenergized, the following circuit is established for the energization of the called line relay 259: battery 80 left-hand winding of said relay, conductor 249, back contact and lower armature of relay 252, lower armature and contact of relay 253, brush 236, terminal 243, over the loop at substation B', terminal 242, brush 235, contact and upper armature of relay 253, conductor 254, upper armature and back contact of relay 252, through the right-hand winding of relay 259 to ground. Relay 259 by attracting its right-hand armature closes 85 a circuit from battery, side-switch arm 234, position 3, through winding of relay 256, conductor 260, front contact and right-hand armature of relay 259, to ground at the off-normal contact 247. Relay 256 energizes 90 and interrupts the above traced circuit for the ringing relay 252, thereby bringing to a close the ringing operation. Conversation may now take place, talking current being transmitted to the calling line through the 100 windings of relay 226 and to the called line through the windings of relay 259. At the termination of conversation, the calling party, by replacing his receiver on the switch-hook, causes the restoration of the 105 switches in the manner already described.

Assuming that after having completed his conversation with the subscriber at the substation B', the calling subscriber at A' desires to converse with another party in the 110 same exchange. He may do so without necessitating the restoration of the complete train of switches involved in the establishment of the original connection. To accomplish this, it is only required that the calling 115 subscriber manipulate his dial 208 to transmit a special series of eleven impulses to the connector C. For each one of these line interruptions, the line relay 226 is intermittently deenergized and energized. The right-hand armature of said relay is so constructed as to coöperate with its make-before-break contact 261 in such a manner that battery potential is applied to the conductor 262 once during retraction and again during attraction of said armature. For eleven impulses sent to the relay 226, the result is that the following circuit is momentarily closed twenty-two times in succession: battery, 120 make-before-break contact 261, right-hand 125 contact 261, right-hand 130

armature of relay 226, conductor 262, through the winding of solenoid 263, side-switch arm 264 to ground. Solenoid 263 is made slow to attract its plunger 265 such that it is necessary to send at least twenty-two consecutive impulses to said solenoid before its plunger is attracted to its full forward position. Plunger 265, therefore, operates to close the contact 266, which establishes a circuit from battery, through the winding of relay 213, brush 218, terminal 267, contact 266, side-switch arm 264, position 3, to ground. Relay 213 energizes and locks up over a circuit from battery, through the winding of relay 213, contact and outer right-hand armature of said relay, to ground at the primary off-normal contact 268. Relay 213 closes a circuit for the release magnet 215 from battery, through the winding of said magnet, contact 251, conductor 269 to ground at the inner right-hand armature and front contact of relay 213. Magnet 215 is thereby energized to restore the selector switch S^2 to its normal position. The test brush 221, on leaving the terminal 225, interrupts the previously traced circuit for the application of ground potential to the test wire 212 at selector S^2 , but relay 213 at its left-hand armature and make-before-break contact 214 has already applied a substitute ground to the wire 212, which thereby prevents the release of any of the switches preceding the selector S^2 . The test brush 221 on leaving the terminal 225 furthermore causes the opening of the circuit for relay 210, which therefore deenergizes. Relay 210 on retracting its armatures prepares the above traced circuit for the line relay 209 in series with the calling line since the latter is closed at this time. Relay 209 energizes before the switch has had time to fully restore to its normal position, and at its upper armature applies ground to the test wire 212 for a purpose which will presently be described. As soon as the switch S^2 reaches its normal position, contact 268 is opened and relay 213 thereby retracts its left-hand armature to remove ground from the test wire 212. Relay 209 as above described has, however, in the meantime, applied a substitute ground to said test wire which prevents the release of the preceding switches, until relay 213 has had sufficient time to retract its inner right-hand armature and apply a holding ground to the test conductor 212 over the following circuit: inner right-hand armature and back contact of relay 213, front contact and upper armature of relay 211, contact 214 to the wire 212. As soon as the brushes 219 and 220 break engagement with terminals 228 and 229 upon the restoration of switch S^2 , the circuit of line relay 226 at the connector switch C is opened, resulting in the release of said connector in the manner already described.

The subscriber at A' has thus been enabled to restore the connector C and selector S^2 without having disturbed any of the preceding switches employed in the establishment of the connection to the called line. He may now proceed to set other switches corresponding to those which have been released to thereby extend his line into connection with the lines of other subscribers. 70

What is claimed is:

1. In a telephone system, a calling and a called line, senders associated with said lines, automatic switches for interconnecting said lines, means controlled by the operation of the calling subscriber's sender for setting 80 the automatic switches, means for releasing all of the set switches, and means responsive to a definite operation only of the calling subscriber's sender for releasing only a portion of the set switches. 85

2. In a telephone system, a calling and a called line, an impulse sender associated with the calling line, selective switches for interconnecting said lines, impulse responsive means operated by impulses sent from said sender for setting the automatic switches, means under the control of the calling subscriber for releasing all of the set switches, and means responsive to not less than a definite number of impulses sent by said sender 95 for releasing a portion only of the set switches.

3. In a telephone system, telephone lines, a train of automatic switches for interconnecting said lines, means for setting said 100 switches, and means effective after any switch in the train has been set to cause the release thereof without releasing the remaining set switches.

4. In a telephone system, a plurality of 105 lines, a train of automatic switches for establishing a connection between any two of said lines, means for setting said switches, and means under the control of one of said lines for releasing any set switch in said 110 train without releasing the remaining set switches in said train.

5. In a telephone system, a calling and a called line, a train of automatic switches for interconnecting said lines, means for setting 115 said switches, and means under the control of the calling subscriber for releasing any set switch in said train without releasing the remaining set switches.

6. In a telephone system, telephone lines, 120 a train of automatic switches for interconnecting said lines, means for setting any number of the switches in said train, means for operating the switch next succeeding the last set switch to release said last set switch 125 without releasing the preceding set switches in said train.

7. In a telephone system, a calling and a called line, a series of automatic switches for interconnecting said lines, means under the 130

control of the calling line for setting successively any number of the switches in said series, and means under the control of the calling line for operating one of the switches 5 succeeding the last set switch in the series for releasing said last set switch.

8. In a telephone system, telephone lines, a series of automatic switches each having a plurality of separate movements for inter- 10 connecting said lines, means for setting any number of said switches, and means for operating in its primary movement one of the switches succeeding the last set switch for releasing said last set switch.

15 9. In a telephone system, a calling and a called line, a train of automatic switches for interconnecting said lines, means for setting the successive switches constituting any portion 20 of said train of switches, means controlled by the calling line for releasing all

of the set switches, and means controlled by the calling line for releasing only the last set switch.

10. In a telephone system, a calling and a called line, a series of impulse operated selective switches each having a primary and a secondary movement for interconnecting said lines, impulse sending means associated with the calling line for setting any number of the switches of said series of switches, 25 and means responsive to said sending means for advancing to a definite position in its primary movement the switch next succeeding the switch last set in said train, whereby said last set switch is restored to normal 30 without restoring the remaining set switches in the series.

In witness whereof, I hereunto subscribe my name this 21st day of May A. D., 1918.

HENRY P. CLAUSEN.
